UNITED STATES PATENT OFFICE.

ANTHONY COSTA, OF CLEVELAND, OHIO, ASSIGNOR TO THE GRAVITY CARBURETER COMPANY, OF CLEVELAND, OHIO, A CORPORATION OF OHIO.

CARBURETER.

1,253,577.

Specification of Letters Patent. Patented Jan. 15, 1918.

Application filed December 3, 1915. Serial No. 64,911.

To all whom it may concern:

Be it known that I, ANTHONY COSTA, a citizen of the United States, and a resident of Cleveland, county of Cuyahoga and State of Ohio, have invented a new and useful Improvement in Carbureters, of which the following is a specification, the principle of the invention being herein explained and the best mode in which I have contemplated applying that principle, so as to distinguish it from other inventions.

The present improvements relate to a carbureter of the type in which the fuel supply is controlled directly by a valve, which is in turn controlled by means of the suction in the manifold leading to the engine, so that as soon as the engine stops and the suction in the manifold is reduced to zero, the fuel supply valve will be closed. The chief difficulty in the past with this type of carbureters, which are usually known as mixing valves, has been to secure a proper regulation of the mixture, and to vary the amount of fuel in proportion to the amount of air that is drawn through the carbureter. The present invention has been developed to provide a means for securing a very accurate control of the amounts of gasoline and air, which means may be adjusted in a simple manner from the outside of the carbureter. To the accomplishment of the foregoing and related ends, said invention, then, consists of the means hereinafter fully described and particularly pointed out in claims.

The annexed drawing and the following description set forth in detail certain mechanism embodying the invention, such disclosed means constituting, however, but one of various mechanical forms in which the principle of the invention may be used.

In said annexed drawing:—

Figure 1 is a plan view of my device; Fig. 2 is a vertical section on the line 2—2 Fig. 1; Fig. 3 is a section on the line 3—3, Fig. 2; and Fig. 4 is a section on the line 4—4, Fig. 2.

A casing 1 of any suitable type may be provided, although preferably this casing will be as small as possible, and of the construction illustrated in Figs. 1 and 3, in which it is shown as a vertically cylindrical casing having a lateral air opening 2 in one side, and a fuel supply conduit 3 extend-

ing centrally through the air opening and then leading exteriorly of the same to a connection 4. Vertically, and preferably centrally disposed in the casing 1, is a conduit 5, connection to the fuel supply conduit 3, and provided both above and below the point of connection with stuffing boxes 6 and 7.

Mounted upon the upper end of the conduit 5, is a fuel supply nozzle 8 having preferably a lateral discharge, and as here shown, a plurality of such lateral discharge openings 9. This discharge nozzle is formed with a vertically projecting extension 10 which is provided with a central passage 11 therethrough, adapted to receive a rod 12 provided at its lower end with a needle valve 13 for the purpose of closing the fuel supply conduits in the same manner to be explained hereinafter. Attached to the rod 12 by means of a yoke 14 is a ring 15 constructed to normally partially close the passage to the casing about the nozzle and to also substantially close the discharge ends of these nozzles as shown in Fig. 1. Furthermore, the ring will be of sufficient thickness to maintain this partial closure both of the passage about the nozzle, and of the nozzles while moving through a certain vertical range. It is obvious therefore, that if the ring is given various vertical positions with respect to the nozzles, it will have correspondingly different amounts of travel before the air passage about these nozzles is fully opened. The attachment of the yoke 4 and rod 12 is by means of a pin 30 set in the yoke and passing through an elongated slot 31 in the rod. The object of this lost motion connection is to permit the ring 15 and yoke 14 to acquire a certain momentum before they pick up the valve 13 which by reason of its tapered form, often sticks slightly and must be lifted with a certain amount of force.

Adjustably mounted in the fuel supply conduit in the casing is a seat 16, formed in the top of a rod 17 which is hollow for a part of its length, and is provided with lateral apertures 18 leading to the hollow portion, these apertures permitting the entrance of fuel from the lateral fuel conduit 3 to the interior of this rod, and therefore to the upper part of the fuel nozzle. The upper

end of this rod is threaded, as indicated, and therefore has an adjustable engagement in the fuel nozzle as indicated in Fig. 1. The seat 16 in the top of this rod is adapted to 5 be closed by means of the needle valve 13 attached to the rod 12, and this needle valve, and also, of course, the ring 15 which is attached thereto, are normally maintained in their lowest position by means of a single 10 spring 19 disposed within the extension on the fuel nozzle. The hollow rod 17 extends exteriorly of the casing to the bottom, where it is provided with a handle 20 for adjustment, and it will be seen that by moving 15 this rod upward through the fuel conduit, it will force the needle valve 13 upward, and with it the ring 15 which closes the air passage about the nozzles. Thus the initial position of the ring will be varied without 20 opening the valve in the fuel supply conduit, and when the ring 15 is finally opened it will have to move only a short distance, and thus will open the fuel valve a correspondingly smaller amount than it would be opened if the ring moved through its 25 normal range of movement, as would be necessary if the ring were positioned as shown in Fig. 2, where it is directly opposed to the fuel nozzles.

30 By means of the mechanism described above, it is possible to secure a very accurate adjustment of the fuel and air, and this is secured without the usual complicated mechanism which is employed where a carbureter 35 of the float type is used. The difficulties which have usually been met with in the mix-valve type of carbureters, are in the present construction entirely eliminated, and this is secured by means of a very simple 40 construction having but one moving and one adjustable part.

It will be seen that the ring 15, when in the position shown in Fig. 2, will partially close the inlet opening for the air past the 45 nozzles 9 although a small amount of air will pass by these nozzles through the semi-circular openings 35 around the ends of the same. When the motor is started some air will be drawn through these semi-circular 50 holes 35, and in this way any sudden blowing open of the ring valve 15 is prevented. Instead, this valve will be opened gradually, but will acquire sufficient momentum to pull the valve 13 open, after a certain amount of 55 travel, in case the latter member, by reason of its contour, should stick. In this way it is possible to use a very gradually tapered pin or valve 13 which affords a very accurate and gradual opening of the fuel valve. The 60 fuel economy of the carbureter is greatly increased by this feature.

Other modes of applying the principle of my invention may be employed instead of the one explained, change being made as regards the mechanism herein disclosed, pro-

vided the means stated by any of the following claims or the equivalent of such stated means be employed.

I therefore particularly point out and distinctly claim as my invention:—

1. In a carbureter, the combination of a casing constituting a carbureting chamber, a plurality of radially disposed fuel nozzles terminating equidistantly from the wall of such chamber, a valve normally closing all 75 of said nozzles, an air valve normally disposed between said nozzles and the wall of such chamber, said nozzles being formed with recesses about them permitting the passage of air in the closed position of said 80 valve.

2. In a carbureter, the combination of a casing constituting a carbureting chamber, a fuel supply nozzle terminating centrally in said casing, a gradually tapered valve 85 normally closing said fuel nozzle, an air valve normally partially closing the passage about said fuel nozzle and positioned to have a certain amount of travel before fully opening, and means adjustably connecting said valves and adapted to vary the amount of travel of said air valve before movement of said fuel valve begins.

3. In a carbureter, the combination of a casing constituting a carbureting chamber, 95 a fuel supply nozzle terminating centrally in said casing, a gradually tapered valve normally closing said fuel nozzle, an air valve normally partially closing the passage about said fuel nozzle and positioned to 100 have a certain amount of travel before fully opening, and lost motion connections between said two valves permitting said air valve to have a certain amount of travel before said fuel valve is opened.

4. In a carbureter, the combination of a casing constituting a carbureting chamber, a fuel supply conduit mounted centrally therein, a disk connected to the top of said fuel supply conduit and provided with a series of laterally extending conduits connecting with such fuel supply conduit, an air valve disposed between said disk and the wall of said casing and partially closing the 110 passage therebetween, a fuel valve extending into said disk and normally closing said fuel conduit, and lost motion connections between said two valves permitting a certain opening movement of said air valve before opening 115 of said fuel valve begins.

5. In a carbureter, the combination of a casing constituting a carbureting chamber, a fuel supply conduit mounted centrally therein, a disk connected to the top of said fuel supply conduit and provided with a series of laterally extending conduits connecting with such fuel supply conduit, an air valve disposed between said disk and the wall of said casing and partially closing the 125 passage therebetween, a gradually tapered 130

fuel valve extending into said disk and normally closing said fuel conduit, and lost motion connections between said two valves permitting said air valve to travel a certain 5 distance before opening of said fuel valve begins.

6. In a carbureter, the combination of a casing constituting a carbureting chamber, a fuel supply conduit mounted centrally 10 therein, a disk connected to the top of said fuel supply conduit and provided with a series of laterally extending conduits connecting with such fuel supply conduit, said disk being provided with recesses about the 15 ends of such conduits, an air valve disposed

between said disk and the wall of said casing and partially closing the passage therebetween, a gradually tapered fuel valve extending into said disk and normally closing said fuel conduit, and lost motion connections between said two valves permitting said air valve to travel a certain distance before opening of said fuel valve begins. 20

Signed by me this 30th day of November, 1915.

ANTHONY COSTA.
